UNITED STATES PATENT OFFICE.

WILLIAM ROGERS, OF HARTFORD, CONNECTICUT.

DESIGN FOR HANDLES OF SPOONS AND FORKS.

SPECIFICATION forming part of Design No. 11,761, dated May 4, 1880.

Application filed March 24, 1880. Term of patent 3½ years.

To all whom it may concern:

Be it known that I, WILLIAM ROGERS, a citizen of the United States, residing at Hartford, in the county of Hartford and State of Connecticut, have invented and produced a new and original Design for the Handles of Spoons, Forks, &c., of which the following is a specification, reference being had to the accompanying drawing, forming part thereof, in which is represented a front view of a fork having my newly-designed handle.

The invention relates to a design for the handles of spoons, forks, and like articles of table-service; and it consists in the peculiar configuration of the upper part of the handle in connection with a hexagonal panel containing diamond-shaped inclosures and ornaments.

It consists, also, in the representation of a bow-knot of ribbon, securing pendent branches with leaves and tendrils, placed under the upper panel of ornamentation of the handle.

To describe the invention more fully, starting from the body of the article, the handle is provided, nearly half-way of its length, (or thereabout) with a boss, *a*, and from there gradually expands in two curved lines, *b b*, terminating in two nearly straight lines, *c c*, converging toward the semicircular tip *d*, but united under said tip by a line, *e*, at right angle with the axis of the fork, and a fillet, *k*, follows without break the contour of the above-mentioned lines *b c e*. Within said

fillet is placed, at the upper end of the handle, a panel, *f*, made hexagonal in form by locating the bottom line, *g*, thereof parallel with the upper line, *e*, and retaining the lines and angles at the upper part of the fillet to complete said hexagonal form. Within this panel is placed a series of diamond-shaped inclosures, *h*, containing small ornaments on a bright or matted ground. Under this panel is embossed the representation of a bow-knot of ribbon, *m*, securing together branches *n*, having leaves, flowers, and tendrils. Starting 45 upward from the boss *a* is placed a plant in bloom, with its wavy stem resting in a light vase, the top of said plant being at a suitable distance from the bow-knot *m*, as represented.

I claim—

1. The herein-described design for articles of table-service, consisting of a handle having a hexagonal panel, *f*, containing a series of diamond-shaped inclosures, *h*, and ornaments, substantially as shown and described. 55

2. The design for articles of table-service, consisting of a handle having a hexagonal panel at the upper end, and under said panel the representation of a bow-knot of ribbon securing pendent branches with leaves, substantially as shown and described. 60

WILLIAM ROGERS.
